UNITED STATES PATENT OFFICE.

ALFRED F. SANFORD, OF KNOXVILLE, TENNESSEE.

RADIO APPARATUS.

Application filed August 18, 1925. Serial No. 51,068.

This invention relates particularly to means for facilitating placing and replacing a radio receiving apparatus into tune with the apparatus of various radio sending stations.

5 The chief object of this invention is to provide means whereby, when a tuning member in a receiving set has, by trial or manipulation, been put into tune with a chosen sending station, a record or notation can be made on 10 the apparatus which will enable the operator to subsequently shift an appropriate part or parts of the apparatus as indicated by said record to again put said receiving apparatus into tune with the same sending station without 15 the need of repeating trial to again find the required positions for said parts.

A further object of this invention is to provide ample surface capacity for making such records or notations.

20 A further object of this invention is to provide the sending station finding mechanism in the form of an attachment adapted to be placed adjacent a previously-manufactured receiving set and connecting the attachment with a tuning shaft of said receiving set.

In the accompanying drawings,

Fig. 1 is a front elevation of a receiving set with my improved attachment applied thereto;

30 Fig. 2 is an upright section on the line 2—2, of Fig. 1, looking toward the right, only the front part of the ordinary receiving set being shown;

35 Fig. 3 is a section on the line, 3—3, of Fig. 1, looking in the direction of the arrows;

Fig. 4 is a section similar to Fig. 2, the transmission gearing consisting of three, instead of two spur gear wheels.

Referring first to Figs. 1, 2 and 3, G is the 40 front wall of an ordinary receiving set. G¹ is the base and G² is the top wall of said set. G³ is the tuning shaft to which my improved attachment is to be connected for the purpose of turning said shaft for tuning. T is any 45 table top or platform upon which the receiving set and the attachment are supported.

The parts of the attachment and their operation will now be described.

A horizontal base, A, is supported on the 50 table, T, by means of three upright screws extending through and threaded in the base, the lower ends of the screws bearing on the table. By means of these screws, the height of said base may be adjusted for a purpose to be 55 make clear further on. A column, B, has a

foot, B¹, resting on the base, A, and immovably secured thereto by means of screws B².

The upper part of the column has a slot, B³, parallel to the wall, G, and extending downward from the upper end of the column 60 far enough to make room for the disc, D, which surrounds and is fixed on the horizontal shaft, C, resting in bearings, B⁴, formed in the upper part of the column. The shaft, C, projects forward through the outer bearing, B⁴. A hand knob, C¹, is mounted on said outer end and fixed thereto, in order that turning said knob will cause the turning of said shaft. The other end of said shaft extends 65 rearward beyond the rear bearing, B⁴. A spur gear wheel, C², surrounds and is fixed to said shaft. Said shaft meshes with a spur gear wheel, F, which has an elongated hub, F¹, of insulation extended toward the wall, G. Said wheel and the greater part of said hub 70 surround and are turnable on a journal, F², which is rigid on the adjacent part of the column, B. The journal, F², has a circumferential channel, F³. Screws, F⁴, extend through the hub and into said channel and thus serve 75 as keys to keep the hub and the wheel, F, from moving away from the column, B.

By means of the adjusting screws, A¹, the height of the attachment has been adjusted to bring the journal, F², to the height of the tuning shaft, G³, thus allowing the moving of the attachment toward the wall, G, until the hub, F¹, has surrounded the outer end of the tuning shaft. The set screw, F⁵, extends radially through the hub, F¹, and bears against the 80 tuning shaft, G³, to bind the hub and the shaft together for movement in unison.

It will now be seen that turning the hand knob, C¹, will cause the turning of the shaft, C, the disc, D, the spur gear wheels, C² and F, the hub, F¹, and the tuning shaft, G³. It will 85 also be seen that these same movements may be effected by grasping the edge of the disc, D, and turning it. In this manner, the ratio of movements is modified, and movement at 90 the edge or rim of the disc being much reduced at the spur gear wheel, C².

A guide or indicator, E, extends over the 95 rim or edge of the disc and reaches to and is secured to the two parts of the column, B. In 100 the form shown by the drawings, the forward part of the indicator is slotted sufficiently to permit reaching through the slot with a writing instrument and placing symbols or other writing on the disc.

The two spur gear wheels are preferably made of different diameters, in order that the velocities of the shafts, C and G³, will be different. The drawings show the wheel, C², made smaller, in order that the shaft, C, may turn the faster, whereby the disc, D, is turned faster than is the shaft, G³. Thus a larger part of the surface of the disc is made to pass the guide or indicator, E, during a fractional 10 rotation of the tuning shaft. The particular proportion or ratio of these gear wheels in the drawings is two to one. In many receiving sets now in use, the tuning shafts make only approximately a one half turn. Accordingly, this two to one gearing provides for a full rotation of the disc, D, during the half turning of the tuning shaft. Thus the entire outer face of the disc is made available to receive indicia showing the positions on 20 the disc in relation to positions of the tuning shaft in its range of turning.

At the left of the tuning shaft, G³, a tuning shaft, I, is applied to the wall, G, and on said shaft is fixed an ordinary dial, I¹. A tuning shaft, J, is similarly applied to the wall, G, at the right of the shaft, G³, and a dial, J¹, is similarly applied to the shaft, J. These are parts of the original apparatus.

The dials, I¹ and J¹, have the usual graduations along only one half of the rim, this being because those shafts are to be given only a one half turn, as has already been described in connection with the shaft, G³. Provision is made for placing on the disc, D, indicia of the positions of each of the three tuning shafts when they have been set to bring this receiving apparatus into tune with a chosen sending station. After the three shafts have been thus positioned, the initials of the sending station and the name of that station may be entered on the portion of the disc which is exposed through the slot of the indicator, E. Associated with this entry, there are to be placed numbers indicating the positions of the dials, I¹ and J¹. On the outer face of the wall, A, and above each dial, I¹ and J¹, is an arrow. The number under each of these arrows is to be made a part of this record on the disc, so that for thereafter re-setting the 40 tuning shafts, the disc is turned to bring the record into the slot of the indicator, and each dial is then turned to bring the number of the record into the indicator slot. Fig. 1 of the drawings shows the disc divided into four 50 zones which are concentric to the shaft, C. The inner of said zones is to receive the initials of sending stations. The next of said zones is to receive the location of the station. The third of said zones is to receive figures 60 representing the number which is under the arrow on the dial, I¹, when the shaft, I, has been set, and the fourth or outer of said zones is to receive the figures representing the number under the arrow on the dial, J¹, when the 65 shaft, J, has been set. In the drawing, "60"

indicates the position of the dial, I¹, and "45" indicates the position of the dial, J¹. "WMBF" and "Miami," indicate the station, and these four entries indicate the position of the disc, D, when the middle tuning shaft, G³, is in tuned position. The drawing shows below the indicator a record for Chicago. To again tune for Chicago, the disc, D, is to be turned to bring the Chicago record into the slot of the indicator. That brings the middle tuning shaft, G³, into tune with Chicago. Then the dial, I¹, is turned to bring "44" under the adjacent arrow, and the dial, J¹, is turned to bring "47" under the adjacent arrow. Above the indicator, the drawing shows a record of Cuba. To again get into tune with that station, the disc is to be turned until that record is in the indicator slot, and then the dials, I¹ and J¹, are turned to "70" and "73," respectively.

In the form above described, to turn the three tuning shafts in the same direction, the disc, D, must turn in opposition to the direction of turning of the dials, I¹ and J¹. This is due to the operation of the two spur gear wheels, C² and F. In Fig. 4, this gearing is modified to provide the same direction of rotation for the dials and the disc. This is accomplished by placing an idle spur gear wheel, H, between the spur gear wheel, C² and F, a journal, H¹, fixed on the column, B, rotatably supporting the idle wheel, H.

In lieu of writing or marking directly on the face of the disc, a removable sheet of paper or similar material may be placed on the disc to serve as the record-receiving surface.

While the drawings show my mechanism applied to the intermediate of three tuning shafts, it will be understood that the mechanism may be applied to any tuning shaft. Probably the most sensitive or controlling shaft should be chosen.

I claim as my invention,

1. In a portable structure adapted to be placed near a radio receiving set and supported independently of said set as a companion structure, the combination of a base, driving mechanism having a member adapted to be placed into alignment with and connected with a tuning shaft of the receiving set, and a member in operative relation with said driving mechanism and bearing a record-receiving surface whereby said record-receiving surface is given movement in relation to the turning of the tuning shaft, substantially as described.

2. In a portable structure adapted to be placed near a radio receiving set and supported independently of said set as a companion structure, the combination of a base, driving mechanism having a member adapted to be placed into alignment with and connected with a tuning shaft of the receiving set, and a rotary member in operative relation with said driving mechanism and bear-

ing a record-receiving surface whereby said record-receiving surface is given movement in relation to the turning of the tuning shaft, substantially as described.

5. 3. In a portable structure adapted to be placed near a radio receiving set and supported independently of said set as a companion structure, the combination of a base, driving mechanism having a member adapted to be placed into alignment with and connected with a tuning shaft of the receiving set, and a member in operative relation with said driving mechanism and bearing a record-receiving surface whereby said record-receiving surface is given rapid movement in relation to the turning of the tuning shaft, substantially as described.

4. In a portable structure adapted to be placed near a radio receiving set and supported independently of said set as a companion structure, the combination of a base, driving mechanism having a member adapted to be placed into alignment with and connected with a tuning shaft of the receiving set, and a rotary member in operative relation with said driving mechanism and bearing a record-receiving surface whereby said record-receiving surface is given rapid movement in relation to the turning of the tuning shaft, substantially as described.

5. In a portable structure adapted to be placed near a radio receiving set and supported independently of said set as a companion structure, the combination of a base, driving mechanism having a member adapted to be placed into alignment with and connected with a tuning shaft of the receiving set, and a rotary disc in operative relation with said driving mechanism and bearing a record-receiving surface whereby said record-receiving surface is given movement in relation to the turning of the tuning shaft, substantially as described.

6. In a portable structure adapted to be placed near a radio receiving set and supported independently of said set as a companion structure, the combination of a base, driving mechanism having a member adapted to be placed into alignment with and connected with a tuning shaft of the receiving set, and a rotary disc in operative relation with said driving mechanism and bearing a record-receiving surface whereby said record-receiving surface is given rapid movement in relation to the turning of the tuning shaft, substantially as described.

7. In a portable structure adapted to be placed near a radio receiving set and supported independently of said set as a companion structure, the combination of a base, driving mechanism having a member adapted to be placed into alignment with and connected with a tuning shaft of the receiving set, a rotary member in operative relation with said driving mechanism and bearing a record-re-

ceiving surface whereby said record-receiving surface is given movement in relation to the turning of the tuning shaft, and indicating means adjacent the record-receiving member, substantially as described.

8. In a portable structure adapted to be placed near a radio receiving set and supported independently of said set as a companion structure, the combination of a base, driving mechanism having a member adapted to be placed into alignment with and connected with a tuning shaft of the receiving set, a member in operative relation with said driving mechanism and bearing a record-receiving surface, whereby said record-receiving surface is given movement in relation to the turning of the tuning shaft, and means for adjusting the height of said structure, substantially as described.

9. In a portable structure adapted to be placed near a radio receiving set and supported independently of said set as a companion structure, the combination of a slotted column in which are horizontal bearings, a driving shaft in said bearings, a disc in the slot of said column and surrounding and fixed to said shaft, and driving mechanism in operative relation with said shaft and adapted to be connected with a tuning shaft of the receiving set, substantially as described.

10. In a portable structure adapted to be placed near a radio receiving set and supported independently of said set as a companion structure, the combination of a base, driving shaft, a rotatable coupling adapted to engage the tuning shaft of a receiving set, gearing intervening the driving shaft and said coupling, and a member in operative relation with the driving shaft and bearing a record-receiving surface, substantially as described.

11. In a portable structure adapted to be placed near a radio receiving set, the combination of a driving mechanism having a member adapted to be placed into alignment and connected with a tuning shaft of the receiving set, and a member in operative relation with said driving mechanism and bearing a record-receiving surface whereby said record-receiving surface is given movement in relation to the turning of the tuning shaft.

12. In a portable structure adapted to be placed near a radio receiving set, the combination of driving mechanism having a member adapted to be placed into engagement with a tuning shaft of the receiving set and while so engaged be rotated for rotating said shaft, and a member in operative relation with said driving mechanism and bearing a record-receiving surface whereby said record-receiving surface is given movement in relation to the turning of said shaft.

13. In a portable structure adapted to be placed near a radio receiving set, the combination of a base, mechanism having a member adapted to be placed into engagement with a

tuning shaft, means for turning said member for turning said shaft, means for adjusting the height of said base to bring said connecting member to the height required for connecting with said shaft, and a member in operative relation with said driving mechanism and bearing a record-receiving surface, whereby said

record-receiving surface is given movement in relation to the turning of the tuning shaft.

In testimony whereof I have signed my ¹⁰ name, this 29th day of July, in the year one thousand nine hundred and twenty-five.

ALFRED F. SANFORD.
